APPARATUS FOR THE EXTRACTION OF CELLULOSIC FIBERS FROM VEGETABLE MATERIAL

Umberto Pomilio, Rome, Italy, assignor to Pomilio Corporation Limited, London, England

Application July 16, 1937, Serial No. 153,993
In Great Britain August 15, 1936

3 Claims. (Cl. 92—7)

The invention is for improvements in or relating to apparatus for the extraction of cellulosic fibers from vegetable material and particularly from vegetable material such as the stalks of wheat, barley, oats, rice and other cereals, and of flax, maize, cotton, hemp, and from material such as sisal, phormium tenax, bagasse, different grasses such as esparto, tow-residues and residues from the manufacture of textile materials. One of the objects of the invention is to produce cellulosic fibers suitable for the manufacture of high-grade and other forms of paper and cardboard and the like. The cellulosic fibers which are present in the materials set out above are for the most part embedded in ligneous or woody matter encrusted with waxes, resins, pectic, mucic and albuminous matters and mineral compounds (e. g. silica compounds). It is already known how to extract the cellulosic fibers by dissolving out the above mentioned substances by treating the vegetable material with alkali and chlorine. The alkali removes a substantial part of the encrusting substances, while the chlorine reacts with the ligneous or woody matter. The concentration of the alkali solution usually employed has been comparatively high, amounting to 10% or higher, and similarly, where chlorine has been used, it has been employed in an undiluted state. Paper manufactured from the resulting fibers has tended to be harsh and crackly.

It has now been found that inter alia the temperature under which the alkali reaction of the above treatment is carried out affects the physical characteristics of the resulting fiber and that high temperature conditions tend to damage the fiber, for example the fiber is increasingly damaged with the increase of temperature over 150° C. The reactions are exothermic and high temperatures are liable to be built up.

According to this invention a process for the extraction of cellulosic fibers from vegetable material comprises treating the material in an open vessel with an alkali solution under conditions for complete reaction with substantially all the encrustants, transferring the treated material to another vessel where it is washed with water, dewatering the material, treating the dewatered material in another open vessel with chlorine gas diluted with air under conditions for complete reaction with substantially all the ligneous matter, removing the material from the last said vessel immediately upon completion of the reaction and immersing the material in a cold water bath, transferring the material from said bath to another vessel and treating it with an alkali solution for dissolving the previously reacted substances. Since the reactions are exothermic, the temperatures built up are dependent inter alia on the velocity at which the reactions take place and

the rate at which the heat evolved is dissipated through the mass of the material and through the walls of the reaction vessels. The velocity at which the reaction takes place in the alkali treatment is dependent on the amount of alkali employed for a given weight of material treated and the strength of the alkali solution.

5 A feature of the invention consists in employing the alkali in quantities only just sufficient to react with and/or dissolve the encrusting substances referred to above, i. e. there must not be an excess of alkali.

10 A further feature of the invention consists in employing an alkali solution, e. g. a caustic soda solution of 1 to 2% strength. When such a solution is employed the relative proportions of the reacting substances are selected to be one part by weight of vegetable material to four to six parts of the solution. The reaction is carried 15 out in an open vessel without pressure for a period from one to four hours according to the nature of the material and the strength of the solution, the extent of the initial disintegration of the material and the temperature may vary 20 from 80° C. to 100° C.

25 In the chlorination treatment, the reaction is also exothermic. As already indicated, the chlorine attacks the ligneous matter to form chloro-lignine compounds. At the same time about half the quantity of chlorine may be converted into hydrochloric acid. The cellulosic fibers, in addition to being adversely affected by high temperatures, are also affected by hydrochloric acid, and the time of contact with it. As 30 already indicated, the temperatures built up are dependent on the velocity at which the reaction takes place and the rate at which the heat is dissipated through the mass of the material and from the walls of the reaction vessels.

35 An important feature of the present invention 40 consists in effecting the chlorination treatment of the vegetable material by causing chlorine gas diluted with air to be conducted through the material. Preferably the chlorine gas and reacting mass are both moist with water. The function 45 of the air is twofold. It reduces the velocity at which the reaction takes place and thus the rate at which heat is evolved, and it also forms a vehicle for conducting away the heat. Furthermore, due to the moisture the resulting hydro-

50 chloric acid is of such a dilution as to be less harmful to the cellulosic fibers than if the chlorine is dry. The proportion of air used with the chlorine is dependent on the nature of the vegetable material being treated and it may vary 55 from .5 to 1. part by volume of air to one part by volume of chlorine, while the moisture content of the chlorine may be up to its saturation point and the moisture content of the mass may be two to five times the dry weight of the mass 60 itself.

The rate at which the chlorine-air mixture is passed through the vegetable material also varies with the nature of the material being treated, since certain materials can be treated at higher temperatures than others without adversely affecting the cellulosic fibers. For example, wheat straw may be treated up to a temperature of 55° C. while hemp straw may be treated up to 65° C. The rate at which chlorine may be passed through the material per pound of the material per hour varies from $\frac{1}{8}$ of a pound to $\frac{1}{2}$ of a pound. The length of the chlorination treatment may vary from half an hour to three hours.

The process according to this invention involves reactions which are controlled as to concentration of solutions, maximum temperature rise and time of treatment, which reactions are carried out successively in separate reaction chambers. A feature of the invention consists in reducing to a minimum the time when the fibres are in contact with the hydrochloric acid resulting from the chlorination, for example, the mass is immersed in cold water as soon as the chlorination is complete.

A further aspect of the invention consists in that the vegetable material is subjected to a further treatment with alkali after the chlorination treatment. As already indicated, the first alkali treatment is carried out under conditions which remove a substantial part of the encrusting substances and do not attack the ligneous matter. Thus, in a sense, the first reaction is a partial reaction. The chlorine treatment reacts with the ligneous matter and forms chloro-lignine compounds. These compounds may not be entirely removed by the immersion in water and the function of the second alkali treatment is to dissolve out these chloro-lignine compounds. The strength of the alkali solution employed for this latter treatment may be as low as .1%. The quantity of solution employed is from 5 to 20 parts by weight of solution to 1 part by weight of vegetable material. As a rough guide the quantity of alkali required in the last alkali treatment is less than half that employed in the first treatment. The temperature at which the reaction takes place may be up to 100° C., and the length of time of the treatment may be as low as a few minutes.

The plant employed may embody an apparatus for mixing solid divided material, such as the aforesaid chopped vegetable material, with a reacting liquor, such as the alkali, which apparatus comprises a hopper or the like arranged above an elongated mixing chamber having a bottom wall sloping in the direction of the length of the chamber, a conveyor in said chamber arranged to traverse the material from the deep end to an outlet at the shallow end, means for introducing the reacting liquor at a controlled rate to said chamber. By these means the material can be arranged to pick up or absorb the desired quantity of liquor during its passage through the mixing chamber. The mixing chamber may be provided with two outlets, one at each end thereof, and with an inverted V-shaped bottom wall and said hopper may be disposed above the apex of the V-shaped bottom wall so that the conveyor is arranged to traverse the material outwardly from said apex to said outlets. An inverted V-shaped deflector may be disposed above the centre of the conveyor and said hopper and means may be provided for adjustably directing the material leaving the hopper

to one side or other of the said V-shaped deflector.

The plant may also embody an apparatus for extracting compacted masses of interlaced fibers from the bottom of treating towers or the like, which apparatus comprises a number of parallel or horizontal shafts spaced apart and having radially extending arms and means for driving adjacent shafts in opposite directions. Means may be provided for varying the distance apart of said shafts.

In an apparatus for the extraction of cellulosic fibers from vegetable material by successive alkali and chlorine treatment, means are provided for converting the material to a floccular state after the removal of the liquor in the alkali treatment and a blower connected with a suitable conduit is provided for conveying by cold air the floccular material in a divided state to the top of the chlorine tower. A receiving chamber may be arranged over the top of the chlorine tower which is provided with a deflecting wall on to which the floccular material is directed by said conduit and is thereby caused to fall into said tower.

The following is a description of one form of apparatus for carrying out the process described above, reference being made to the accompanying drawings in which:

Figures 1a and 1b taken together represent a side elevation of the plant showing diagrammatically the general arrangement.

Figure 2 is a vertical section on the line 2—2 of Figure 1a showing the alkali towers in elevation.

Figure 3 is a section through a tower on the line 3—3 of Figure 1.

Figure 4 is an enlarged view of one of the mixing devices of Figure 2.

Figure 5 is an enlarged view of the mechanism for tilting the hopper nozzle as shown in Figure 4.

Figure 6 is a side elevation of the device shown in Figure 5.

Figure 7 is a plan view of the extractor for the reaction towers.

Figure 8 is an elevation of the arrangement shown in Figure 7.

Figure 9 is a cross section on the line 9—9 of Figure 8.

Assuming stalks or straw of plants, such as are referred to at the commencement of the specification, are to be treated, these are cut into lengths of a few inches and are loaded into hoppers 10 arranged at the top of the apparatus. The apparatus about to be described is designed for producing about 15 tons of cellulose per day. Each hopper is arranged to deliver the material to an apparatus 11 which mixes the stalks with an alkali solution in the required proportions and delivers the mixture to the upper ends of a pair of vertically-arranged reaction towers 12. Each mixing apparatus thus serves two towers, and comprises a long horizontally-disposed chamber 13 open at the top, the lower wall 14 of which is inclined downwardly from each end to the centre to form a V. A screw-conveyor 15 is horizontally-disposed along the length of the chamber and has two sets of helical blades arranged end to end, which blades are oppositely pitched to one another, and are driven by a motor 22. Disposed above the chamber and at the centre of the screw-conveyor is a V-shaped deflector 16. The hopper is arranged to deliver the material on to the deflector through a flexible nozzle 17 which may be swung from one side to the other of the V-shaped

deflector thereby adjusting the relative quantities of the material being fed to the two towers. The movement of the nozzle may be effected by a hand wheel 18 fixed to a worm shaft 19 in engagement with a rack 20 secured to the nozzle. The worm shaft is mounted in a bracket 21 secured to the chamber 15. Caustic soda solution is supplied to the chambers through a conduit 23 and a suitable device for maintaining a constant level of the solution in the V-shaped recess in the bottom of the chamber but which level does not reach the blades of the conveyor. As already indicated, the strength of the solution may be from 1 to 2%. Each end of the chamber is open and the screw-conveyor forces the material mixed with the alkali out through said open ends from which mixture drops into the open end of the reaction tower 12.

The reaction towers may be about 30 feet high and in cross-section are flattened oval-shaped (as will be seen from Figure 3), the smaller dimension being about 15 inches and the larger dimension 8 feet. The conveyor 13 is so arranged as to effect a mixture of straw and solution in proportions of one of straw to four of the solution. Steam is introduced through the walls of the tower by a number of pipes 24 in a zone substantially above the horizontal centre line, e. g. one-quarter of the length from the top. The steam generating plant 25 and main delivery pipe 26 are shown to the left of Figure 1. The mass of material gradually descends under gravity and becomes compacted as it descends, and at the bottom forms a seal which prevents too rapid an escape of the liquid. The time of descent may vary from one to four hours according to the nature of the material and the strength of the caustic solution. During this time the alkali is almost completely used up to form spent liquor of a dark colour. The tower is provided with inspection windows 9 and sockets 8 for thermometers at different heights.

When the mixture arrives at the bottom of the tower it is in the form of compacted interlaced fibers whence it is removed by an extractor 27, the speed of extraction being adjustable; thus, the time of treatment may be varied.

As will be seen from Figure 7 to 9 the extractor comprises two parallel shafts 28 each of which carries a number of star-shaped members 29. The two shafts are rotated through gearing 30 in opposite directions so that the arms of the stars draw the material downward and first move towards one another and then away from one another. The mountings for shafts 28 and the gearing 30 may be so arranged that the distance apart between the shafts may be varied. The gearing may be driven by an electric motor (not shown) the speed of which may be controlled thereby controlling the rate of withdrawal of the material from the bottom of the towers.

The fibers are separated from the spent liquor by a screening device 31 through which the material is fed by a screw conveyor 32. The screening device is formed in two parts 33, 34 arranged end to end along the length of its conveyor and the part at the outlet end 34 receives a supply of wash water through a pipe 35 which wash liquor is delivered by an outlet pipe 36 to a tank 37. The washed and partly-treated fibers are delivered by the conveyor through an outlet conduit 38 to a screw-press 39 where the remainder of the spent liquor is squeezed out of them and delivered to a tank 40 through a pipe 41. The consolidated mass is then passed through a conduit

42 to an opener 43 having spiked rollers or combs where it is converted into a floccular state. It is then raised by air blowers 44 through suitable conduits 45 to a receiving chamber 46 arranged above the upper end of a set of chlorinating towers 47. The upper ends of the chlorinating towers are open and the conduits 45 are directed on to a deflecting plate 48 in the collecting chamber 46 whereby the floccular material is caused to fall into the towers. This treatment results in the floccular material having a dryness factor of from about 25 to 40, i. e. 75% to 60% water and 25% to 40% bone dry material.

These towers may also be about 30 feet in height although those shown in the drawings are shorter. They are of a flattened oval shape in cross-section, the general dimensions being the same as those of the alkali towers. Chlorine is introduced into the fibrous mass at a zone about 10 feet from the top of each tower. As already indicated the top of each tower is open but the 10 foot column of fibrous material above the zone is sufficient completely to absorb the chlorine and prevent leakage, and the sealing action is enhanced by the fact that the material is descending. The chlorine is introduced into the zone by pipes 49 which extend from a header pipe 50 through the walls of the tower and stop flush with the inside face, and also by means of a set of pipes 51 which extend downwardly from a header pipe 52. From practical considerations the width between the side walls of the tower cannot be made much less than 15 inches and since chlorine cannot readily penetrate the fibrous material to that extent, the additional vertical delivery pipes are provided. Thus, a comparatively small penetration is required without the necessity of applying substantial pressure to the chlorine. Chlorine with the required degree of moisture may be prepared in an electrolytic plant 53 from which it passes through a delivery conduit 54 to a blower 55 driven by a motor 56. The inlet or suction side of the blower communicates with the atmosphere through a valve 57 and air pipe 58. By adjusting the valve 57 a desired quantity of air may be mixed with the chlorine. The chlorine air mixture is delivered by a pipe 59, to the aforesaid header pipes 49 and 52 through suitable valves 53 and 54. The fibrous material gradually sinks through the tower and is removed from the bottom of the tower by an extractor 55, similar to the aforesaid extractor 27 the speed of extraction being adjustable as in the case of the alkali tower. As in the alkali tower inspection windows 9 and sockets for thermometers are provided.

The material is then delivered by the extractor into a tank 60 having rotating stirrers 61 therein through which tank cold water is circulated. The material passes thence along a trough 62 to a rotating conical sieve 62, the axis of which is horizontal and the angle of inclination of the walls of which is such as to feed the material from the smaller end of the sieve to the larger end. The diluted hydrochloric acid percolates out through the sieve walls into a tank 64 and the fibrous material thus partially freed of acid is passed through screw-presses 65 where it is consolidated. The fibrous material is then passed through a mixing vat 66 containing a weak solution of caustic soda, e. g. a soda solution of 2% concentration or less. The material is treated in this vat for a fraction of an hour and this results in the removal of the chloro-lignine compounds and/or other non-cellulose soluble mat-

ter. Also, any remaining hydrochloric acid or chlorine combines with the caustic soda. Thereafter the fibers are passed through the usual washing and sorting apparatus where knots are removed.

As already indicated the towers both for the alkali and chlorine treatments are provided with thermometers so that the predetermined temperatures of the reactions may be maintained, for example, by controlling the rate of extraction of the material from the bottom of the towers. Furthermore, means are provided for periodically testing the air and moisture content of the chlorine mixture.

The starting material may be considered to contain roughly 50% cellulose constituent and 50% non-cellulose constituent. Each of the first two treatments, i. e. the first alkali treatment and the chlorine treatment, result each in the removal of about 30% non-cellulose constituent, whereas the final alkali treatment results in the removal of 40% of the non-cellulose constituent. The attenuated nature of the treatment in a number of steps and the comparatively slow velocity of the reaction and the comparatively low temperatures under which the reactions are carried out result in a high yield of fibrous cellulose of good quality and suitable for the manufacture of a high grade of paper owing to its strength, softness and pliability.

The stalks of plants, such as are mentioned at the commencement of the specification, contain about 8% lignin by weight of the material and about 42% of waxes, resins, pectic, mucic and albuminous matter, etc. The amount of alkali required for reaction with these latter substances is about half their weight. The chlorine gas reacts with all the lignin and with certain other non-cellulosic materials. It is important that the first alkali treatment should remove only about 30% of the non-cellulosic encrustants, since their presence in the material during the chlorination treatment insures the formation of chloro-lignins which are readily removed by the final alkali treatment. Since only 30% of the encrustants are to be removed by the first alkali treatment, i. e. an amount equal to 15% by weight of the material, and since the encrustants require about half their weight in alkali for the reaction, the weight of alkali required is about 7½% by weight of the raw material or roughly $\frac{1}{8}$ the weight of the raw material.

There remains in the material after the chlorination treatment chloro-lignin and certain other chlor-organic compounds, together with some remaining encrustants. The chloro-compounds, however, require very little alkali for their dissolution and the total amount of alkali required in the last step is less than half that of the first alkali treatment.

It will be appreciated that many modifications may be made to details of the above process and apparatus without departing from the scope of this invention.

I claim:

1. An apparatus for extraction of cellulosic fibers from vegetable material comprising a mixing chamber having a bottom wall sloping in the direction of the length of the chamber, means for introducing the vegetable material into said chamber, a conveyor in said chamber arranged to traverse the material from the deep end to an outlet at the shallow end, means for introducing an alkali solution at a controlled rate to said

chamber, means for directing the mixture from said outlet to the top of a vertical reaction tower open at the top, means for introducing steam into the upper part of the tower, means for extracting at a controlled rate the treated material from the bottom of the tower, means for removing the liquor from the treated material, a second vertical reaction tower open at the top, means for introducing the treated material into the top of the second tower, means for introducing at a controlled rate chlorine diluted with air into the upper part of the second tower, means for extracting the chlorinated material at a controlled rate from the bottom of said tower and for introducing it into a cold water bath, a vessel containing a weak alkali solution, and means for transferring material from the water plant to said vessel.

2. An apparatus for the extraction of cellulosic fibers from vegetable material, comprising an elongated mixing chamber having a bottom wall which slopes downwardly from its outer ends to its centre, means for introducing the vegetable material to the central zone of said chamber, a conveyor in said chamber arranged to traverse material from the centre outwards to an outlet opening at each end of the chamber, means for introducing an alkali solution at a controlled rate to said chamber and means for directing the mixture from each outlet to a separate vertical reaction tower open at the top, means for introducing steam into the upper part of each tower, means for extracting at a controlled rate the treated material from the bottom of each tower, means for removing the liquor from the treated material, another vertical reaction tower open at the top, means for introducing the material to the top of the latter tower, means for introducing at a controlled rate chlorine diluted with air into the upper part of said latter tower, means for extracting the chlorinated material at a controlled rate from the bottom of said tower and for introducing it into a cold water bath, a vessel containing a weak alkali solution, and means for transferring material from the water plant to said vessel.

3. An apparatus for the extraction of cellulosic fibers from vegetable material, comprising a vertical reaction tower open at the top, means for introducing into the top of the tower the vegetable material mixed with alkali solution, means for introducing steam into the upper part of the tower, means for extracting at a controlled rate the treated material from the bottom of the tower, means for removing the liquor from the treated material, a second vertical reaction tower open at the top, means for introducing the treated material into the top of the second tower, means for introducing at a controlled rate chlorine diluted with air into the upper part of the second tower, means for extracting the chlorinated material at a controlled rate from the bottom of said tower and for introducing it into a cold water bath, which means for extracting the material from the bottom of said tower comprises a number of parallel, horizontal shafts spaced apart and having radially-extending arms, means for driving adjacent shafts in opposite directions, a vessel containing a weak alkali solution, and means for transferring material from the water plant to said vessel.

UMBERTO POMILIO.
